DESIGN FOR A BILLFOLD

Charles Weeks, Redwood City, Calif.

Application February 11, 1948, Serial No. 144,396

Term of patent 3½ years

(Cl. D87—3)

To all whom it may concern:

Be it known that I, Charles Weeks, a citizen of the United States and a resident of Redwood City and county of San Mateo and State of California, have invented a new, original, and ornamental Design for a Billfold, of which the following is a specification, reference being had to the accompanying drawing, forming a part thereof, in which:

Figure 1 is a view of one side of the billfold in folded position; and

Figure 2 is a view of the side opposite to that shown in Figure 1, the whole showing my new design.

I claim:

The ornamental design for a billfold, as shown.

CHARLES WEEKS.
